UNITED STATES PATENT OFFICE.

AMOS K. ERSLAND, OF FRUITHURST, ALABAMA.

ADDING-MACHINE.

SPECIFICATION forming part of Letters Patent No. 684,682, dated October 15, 1901.

Application filed February 4, 1901. Serial No. 45,902. (No model.)

To all whom it may concern:

Be it known that I, AMOS K. ERSLAND, a citizen of the United States, and a resident of Fruithurst, in the county of Cleburne and State of Alabama, have invented a new and Improved Adding-Machine, of which the following is a full, clear, and exact description.

The purpose of the invention is to construct an adding-machine containing few parts and not liable to get out of order, the parts being so arranged that they will accurately perform their functions and also so that the numeral-wheels employed may be operated from the exterior of the machine by a lead-pencil, pen-stock, pointer, or the like.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the machine. Fig. 2 is a longitudinal vertical section through the machine, the section being taken between the units and the tens wheels. Fig. 3 is a plan view of the units and tens wheels and the parts coöperating therewith.

Fig. 4 is a view of the periphery of an adding or numeral wheel laid straight. Fig. 5 is a detail perspective view of a spacing-arm which is located between the adding-wheels. Fig. 6 is a perspective view of an actuating-arm carried by the spacing-arm, and Fig. 7 is a side elevation of a portion of a stick or pencil used in operating the device.

A represents a casing, which may be of any desired dimensions and shape, and at the front of the casing a convexed or circular section B is formed. In this convexed or circular section B slots 10 are produced, which extend from a point near the bottom of the convexed or circular section to the top thereof, as is illustrated in Fig. 1. In the bottom portion of the convexed or circular section B of the casing, immediately to the left of the lower portion of each slot 10, an opening 11 is made in the casing, and at these openings 11 the sum-total is read. The openings 10 are of uniform width and length and are placed at equal distances apart. Any desired num-

ber of these openings may be employed. In the drawings five are shown. Usually at the left-hand side of each opening 10 numerals 55 are produced upon the convexed or circular section B of the casing, and these numerals read from "1" to "9;" but a numeral does not appear at the bottom portions of the slots, as shown in Fig. 1, and the numerals are 60 spaced an equal distance.

A shaft 12 is journaled in the sides of the casing A at the convexed front portion of said casing, as shown in Figs. 1 and 2, and on this shaft 12 a series of adding-wheels C 65 is loosely mounted, the adding-wheels corresponding in number to the number of slots or openings 10 in the convexed portion B of the casing. Each adding-wheel C at its periphery is provided with a tally-section 13 at the 70 left and an operating-section 14 at the right, the periphery being suitably divided by the two sections. The operating-sections 14 of the adding-wheels, when the said wheels are properly placed in position in the casing A, 75 appear opposite the openings or slots 10 in the convexed section B of the casing. At the tally-section of each adding-wheel series of numerals are produced at regular intervals apart, each series reading from "0" to 80 "9," and a proper number of such series are arranged on the tally-section of an adding-wheel. These series are fully shown in Fig. 4, in which the periphery of an adding-wheel is shown laid straight. At the operating periphery section of each adding-wheel a series of depressions or recesses 15 is produced, separated one from the other by transverse or diametrical ribs, and said recesses or depressions 15 correspond in position to the 85 position of the numerals on the tally face or section of an adding-wheel, as is shown in Figs. 3 and 4. These depressions appear at the openings or slots 10 in the casing, and any one of the tally-wheels may be turned 90 by introducing the end of a lead-pencil, pointer, or the like 16 into one of the depressions 15 and bearing downward on the pencil, thus revolving the wheel in a downward direction until the pointer or pencil strikes 95 the bottom of the slot 10, into which it was introduced. Preferably the pointer or pencil 16 is provided with an elastic tip 17, secured thereto in any suitable or approved

manner in order to prevent the pencil or tip from slipping as the elastic tip in the operation of the adding-wheel is brought in engagement with the periphery of the same.

- 5 Each adding-wheel is provided at its left-hand side or the side which faces an adjoining adding-wheel with pins 18, corresponding in number to the number of series of numerals on the tally-faces of the wheels, and these 10 pins 18 are placed at equal distances apart below the numeral "5" in each series of numerals.

The adding-wheels C are spaced through the medium of arms D, which arms consist 15 of a forward body portion 19, having an opening 20 therein to loosely receive the shaft 12, and a thinner rear section 21, which constitutes a continuation of the left-hand face of the body-section 19, thus forming a shoulder 20 22 where the two sections of an arm D connect, and in this shoulder a recess 23 is produced at the upper portion of an arm D. Apertures 24 are produced in the side walls of the said recess, as is best shown in Fig. 5. 25 At the rear end of each spacing-arm D an opening 25 is made, and these openings loosely receive a rod 26, which extends from side to side of the casing A through vertical slots 27 made in said casing. Thus the rod 30 26 may be adjusted, and said rod is held in adjusted position by nuts 28, secured upon its outer end and having bearing against the outer faces of the sides of the casing A, as is shown in Fig. 1. The rod 26 is made adjustable, because it makes it more convenient in 35 assembling the parts in the machine, and if for any reason the actuating-lever has to be adjusted the rod 26 has also to be adjusted, or the operation of the wheel by the key and 40 by the carrier device would not be simultaneous, as after the rod is set one is dependent on the other. Each spacing-arm D carries an operating-arm E. One of these operating-arms is shown in detail in Fig. 6 45 and consists of a forward body portion 29, which is pivoted in the recess 23 of a spacing-arm D, the pivot-pin passing through the apertures 24 in the spacing-arm and an aperture at the forward portion of the operating-arm. Each operating-arm 50 29 is provided with a thinner rear section 30, continuous with the left-hand portion of the body-section 29, thus forming a shoulder 31 where the two sections are connected, and at the 55 rear end of the thinner section 30 of each operating-arm a sleeve 32 is formed at its right-hand side. Consequently a recess 33 is produced in the right-hand side of each operating-arm E between its sleeve 32 and its shoulder 31. These recesses 33 permit the passage 60 of the pins 18, carried by the adding-wheels, and the said pins are adapted to turn an adjacent adding-wheel when a number is to be carried over. A spindle 34 is passed through 65 each sleeve 32 of each operating-arm E in direction of the left-hand side of the operating-arm, as shown in Fig. 3, and on each

spindle 34 a dog 35 is pivoted. These dogs are adapted to enter a depression or recess 15 in an adjacent left-hand adding-wheel, as is 70 shown in Figs. 2 and 3. The dogs 35 are held in engagement with the peripheral surfaces of the adding-wheels by springs 36, (shown as coiled around the spindles 34,) attached at one end to an operating-arm and having 75 bearing at the opposite end upon a dog 35. Each operating-arm E is rendered vertically adjustable by screwing a cap 36a upon a post 37, one of which posts is secured to each spacing-arm near its rear end, so that the dogs 35 80 may be made to bear more or less forcibly on the adding-wheels and may be made to act more or less quickly to turn the said wheels, as at each upward movement of each operating-arm E the dog 35, carried by that arm, 85 will be made to ascend a sufficient distance to turn the adding-wheel with which the arm engages a distance of a space between two numerals, or the length of a depression 15 in the periphery of the adding-wheel. As will 90 be seen, the cap 36a moves either up or down; but this does not move the spacing-arm to which the post 37 is secured. A stop-arm 38 is pivoted upon each spindle 34, and, as shown in Fig. 2, each stop-arm extends down 95 through an opening in a detent 39, one of said detents being provided for each of the adding-wheels. These detents are pivoted at their rear ends to brackets 40 or their equivalents, secured to the rear of the casing, and each detent at its forward end is provided with an upwardly-extending toothed head 41. Normally the detents 39 rest at 100 their head portions upon blocks 42, secured to the bottom of the casing A, and in this 105 position of the detents the heads 41 are out of engagement with the peripheral faces of the adding-wheels. Each stop-arm 38 is provided with an exterior thread 43 below the detent through which it passes, and a nut 44 110 is screwed upon the said threaded surface.

In operation, the wheels being initially as shown at Fig. 1, wherein a "0" appears at each of the reading-openings 11, if it be desired to add "5" and "7," for example, the pointer 115 or pencil 16 is introduced in the recess 15 of the units-wheel or the wheel at the right opposite the numeral "5," and the units-wheel is then carried downward until the numeral "5" 120 on the tally-face of the units-wheel appears at the right-hand reading-opening 11, which will happen when the pointer strikes the bottom of the right-hand slot 10. Next the pointer is introduced in the recess 15 of the units-wheel opposite the numeral "7" on the 125 front of the casing, and the units-wheel is then rotated until the pointer or pencil again strikes the bottom of the slot 10, exposing the recessed portion of the units-wheel, and the numeral "2" will appear at the first right-hand reading-opening 11. Five and seven 130 added together will make twelve, and the "1" is carried over to the tens-wheel and will appear at the second right-hand reading-opening

11. This carrying over is accomplished by causing the units-wheel to turn sufficiently to bring one of the pins 18 in engagement with the shoulder 31 of the operating-arm E between the units and tens wheels and raise the said operating-arm to such height that the dog 35 belonging to said arm will turn the tens-wheel one point and cause the numeral "1" to appear at the second reading-opening 5 at the right of the machine and, as has been stated, the total "12" will be read at the front of the machine. The adding is carried out in this manner on the units-wheel when a number in units is to be added to another, 10 but when a number in tens is to be added the units are counted on the units-wheel and the tens on the tens-wheel, and this rule is preserved when units and hundreds are to be added. When an operating-arm E has been 15 raised sufficiently to move the adding-wheel with which its dog engages one point, the pin 18 of the adding-wheel engaging with the operating-arm will clear the shoulder 31, and the said operating-arm may then drop to its 20 normal position, entering the next lower recess 15 in the adding-wheel, since the recess 33 in the operating-arm will permit the arm to clear the pin with which it was in engagement. At the moment that the operating- 25 arm has been brought in position to move an adding-wheel the nut 44 of the stop-arm 38 will engage with the bottom of the detent 39 belonging to the adding-wheel which is turned, raising the said detent and causing 30 the head thereof to enter one of the lower recesses or depressions 15 in the adding-wheel, and thus prevent the wheel from turning by 35 momentum.

Having thus described my invention, I 40 claim as new and desire to secure by Letters Patent—

1. In an adding-machine, an adding-wheel having its periphery provided with a tally and an operating section, the tally-section 45 having numerals produced thereon, an operating-arm, means carried by the wheel for actuating said arm, an adjustable support for the operating-arm, and a dog carried by the operating-arm and adapted to engage recesses 50 in the peripheral face of an adjoining adding-wheel to move the same, as specified.

2. In an adding-machine, an adding-wheel having its periphery provided with a tally and an operating section, the tally-section 55 having series of numerals produced thereon, and the operating-section having depressions corresponding in position to the numerals, pins located on one face of the wheel, one pin for each series of numerals, an operating- 60 arm pivoted at one end to a support located at one side of the wheel, the free end of the operating-arm extending beyond the peripheral face of the wheel, and a dog carried at the free end of the operating-arm and adapted 65 to enter the recesses in the operating-section of an adjoining adding-wheel, the said operating-arm being provided with a shoulder

adapted to be engaged by the said pins, as set forth.

3. In an adding-machine, a shaft, adding-wheels loosely mounted on said shaft and provided with tally and operating sections, spacing-arms mounted on the shaft between the wheels, pins on said wheels extending in direction of an adjoining wheel, operating- 70 arms pivoted to said spacing-arms, and adapted to be engaged and moved by the said pins, and a dog carried by each of the operating-arms and adapted to engage and move an adjacent adding-wheel, substantially as specified. 75

4. In an adding-machine, a shaft, adding-wheels loosely mounted on said shaft, the adding-wheels being provided with tally and operating peripheral sections, the tally-sections of the wheels having series of numerals produced thereon, reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 85 90

5. In an adding-machine, a shaft, adding-wheels loosely mounted on said shaft, the adding-wheels being provided with peripheral tally and operating sections, the tally-sections

of the wheels having series of numerals produced thereon reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 100 105

6. In an adding-machine, a shaft, adding-wheels loosely mounted on said shaft, the adding-wheels being provided with peripheral tally and operating sections, the tally-sections of the wheels having series of numerals produced thereon reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 110 115

7. In an adding-machine, a shaft, adding-wheels loosely mounted on said shaft, the adding-wheels being provided with peripheral tally and operating sections, the tally-sections of the wheels having series of numerals produced thereon reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 120 125

8. In an adding-machine, a shaft, adding-wheels loosely mounted on said shaft, the adding-wheels being provided with peripheral tally and operating sections, the tally-sections of the wheels having series of numerals produced thereon reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 130

9. In an adding-machine, a shaft, adding-wheels loosely mounted on said shaft, the adding-wheels being provided with peripheral tally and operating sections, the tally-sections of the wheels having series of numerals produced thereon reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 135

10. In an adding-machine, a shaft, adding-wheels loosely mounted on said shaft, the adding-wheels being provided with peripheral tally and operating sections, the tally-sections of the wheels having series of numerals produced thereon reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 140

11. In an adding-machine, a shaft, adding-wheels loosely mounted on said shaft, the adding-wheels being provided with peripheral tally and operating sections, the tally-sections of the wheels having series of numerals produced thereon reading from "0" to "9" and the operating-sections of the wheels being provided with depressions corresponding in position to the position of the numerals, spacing-arms located between the said wheels, pins projected from a face of the said wheels in direction of an adjoining wheel, a pin being provided for each series of numerals, operating-arms carried by the spacing-arms, adapted to be raised by the said pins, and dogs carried by the operating-arms, adapted to enter the recesses in the peripheral surface of an adjacent adding-wheel, as specified. 145

arms located between the wheels, pins projecting from one face of the wheel, operating-arms pivoted at one end to the spacing-arms, and adapted to be moved by the said pins, a 5 dog carried by each operating-arm and adapted to engage and move the adjacent wheel, detents pivoted at one end and adapted to engage recesses in the adding-wheels, the said detents being normally out of engagement 10 with the wheels, stop-arms pivotally connected at one end with the operating-arms, the other ends of said stop-arms extending through openings in the detents, and nuts on the said ends of the stop-arms, as set forth. 15 8. An adding-machine, comprising a casing having a curved portion at its front provided with slots or openings, a shaft journaled in the sides of the casing, a series of adding-wheels loosely mounted on said shaft and cor- 20 responding in number to the slots or openings in the curved portion of the casing, each wheel being provided with a tally-section and an operating-section, the operating-sections being arranged opposite the said slots 25 in the casing and provided with depressions, and the tally-sections having series of numerals thereon, pins projected from a face of the wheels in direction of an adjoining wheel, spacing-arms mounted at one end on the shaft

between the said wheels, a rod passing through 30 the other ends of the spacing-arms, the said rod extending through slots in the sides of the casing, means for adjusting the said rod, operating-arms carried by the spacing-arms and adapted to be raised by the pins on the 35 said wheels, and a dog carried by each of the operating-arms and adapted to enter the recesses in the peripheral surface of an adjacent adding-wheel, substantially as specified.

9. In an adding-machine, an adding-wheel 40 having its peripheral face provided with a tally and an operating section, an operating-arm provided with means for engaging and moving the adjoining adding-wheel, a support to which the operating-arm is pivoted, means 45 for actuating the operating-arm from the wheel, a post secured to the support for the operating-arm, and an adjustable cap on said post and on which the operating-arm normally rests, as set forth. 50

In testimony whereof I have signed my name to this specification in the presence of two subscribing witnesses.

AMOS K. ERSLAND.
